(57) **CLAIM**

The ornamental design for lavatory system with multi-use faucet, substantially as shown and described.

DESCRIPTION

FIG. 1 is a raised perspective view of a lavatory system with multi-use faucet showing a basin with an unclaimed multi-use faucet, according to a first embodiment of the invention; FIG. 2 is a top view of the lavatory system with multi-use faucet of FIG. 1;

FIG. 3 is a sectional view of the lavatory system with multi-use faucet taken along line 3-3 in FIG. 2;

FIG. 4 is a bottom view of the lavatory system with multi-use faucet of FIG. 1;

FIG. 5 is a front view of the lavatory system with multi-use faucet of FIG. 1;

FIG. 6 is a rear view of the lavatory system with multi-use faucet of FIG. 1;

FIG. 7 is a right side view of the lavatory system with multi-use faucet of FIG. 1;

FIG. 8 is a left side view of the lavatory system with multi-use faucet of FIG. 1;

FIG. 9 is a lowered perspective view of the lavatory system with multi-use faucet of FIG. 1;

FIG. 10 is a raised perspective view of a lavatory system with multi-use faucet showing a basin with an unclaimed multi-use faucet, according to a second embodiment of the invention;

FIG. 11 is a top view of the lavatory system with multi-use faucet of FIG. 10;

FIG. 12 is a sectional view of the lavatory system with multi-use faucet taken along line 12-12 in FIG. 11;

FIG. 13 is a bottom view of the lavatory system with multi-use faucet of FIG. 10;

FIG. 14 is a front view of the lavatory system with multi-use faucet of FIG. 10;

FIG. 15 is a rear view of the lavatory system with multi-use faucet of FIG. 10;

FIG. 16 is a right side view of the lavatory system with multi-use faucet of FIG. 10;

(Continued)

FIG. 17 is a left side view of the lavatory system with multi-use faucet of FIG. 10;
FIG. 18 is a lowered perspective view of the lavatory system with multi-use faucet of FIG. 10;
FIG. 19 is a raised perspective view of a lavatory system with multi-use faucet showing a basin with an unclaimed multi-use faucet, according to a third embodiment of the invention;
FIG. 20 is a top view of the lavatory system with multi-use faucet of FIG. 19;
FIG. 21 is a sectional view of the lavatory system with multi-use faucet taken along line 21-21 in FIG. 20;
FIG. 22 is a bottom view of the lavatory system with multi-use faucet of FIG. 19;
FIG. 23 is a front view of the lavatory system with multi-use faucet of FIG. 19;
FIG. 24 is a rear view of the lavatory system with multi-use faucet of FIG. 19;
FIG. 25 is a right side view of the lavatory system with multi-use faucet of FIG. 19;
FIG. 26 is a left side view of the lavatory system with multi-use faucet of FIG. 19; and,
FIG. 27 is a lowered perspective view of the lavatory system with multi-use faucet of FIG. 19.
The broken lines shown in the drawings form no part of the claimed design. The surface shading illustrated in the drawings is provided merely to highlight the contour of the design and is not part of the claimed design. All surfaces not shown form no part of the claimed design.

The claim is shown with a symbolic break in its length. The appearance of any portion of the article between the break lines forms no part of the claimed design.

1 Claim, 24 Drawing Sheets
